UNITED STATES PATENT OFFICE.

ROBERT DRURY MARTIN, OF HUMBLE, TEXAS.

DRILL-BIT FOR WELLS.

1,211,331.

Specification of Letters Patent.

Patented Jan. 2, 1917.

Application filed August 7, 1916. Serial No. 113,652.

To all whom it may concern:

Be it known that I, ROBERT D. MARTIN, a citizen of the United States, residing at Humble, in the county of Harris and State of Texas, have invented certain new and useful Improvements in Drill-Bits for Wells; and I do declare the following to be a full, clear, and exact description of the invention, such as will enable others skilled in the art to which it appertains to make and use the same.

This invention relates generally to tools for drilling deep wells, but more particularly to a drill bit of improved construction for such purpose.

Heretofore much difficulty has been experienced in boring deep wells because of the fact that after the rotary bit has been stuck a considerable distance in the ground during the drilling operation a sticky earthy substance, usually gumbo, sticks to the bit and prevents a further efficient operation. Numerous means have been employed in overcoming this difficulty, and among them, water under pressure has been supplied to the bit, but these are still defective because the stream of water does not cover all parts of the bit, and does not come into effective operation until some of the earthy material has actually stuck to the bit.

It is therefore, the object of the present invention to overcome the above difficulty and to improve generally upon the defective devices of this character by the provision of a bit to which water under pressure is supplied to all parts of the same.

The invention consists of certain novel features of construction, and the combination and arrangement of parts as will be hereinafter fully described and claimed.

In the accompanying drawings forming a part of the specification and in which similar reference characters designate like parts throughout the several views, Figure 1 is a front elevation of a bit constructed in accordance with this invention; Fig. 2 is a longitudinal sectional view taken on the plane of the line 2--2 of Fig. 1; and, Figs. 3 and 4 are horizontal sectional views taken on the planes of the lines 3--3 and 4--4 of Fig. 1.

Referring more particularly to the drawings, the reference numeral 1 designates the cylindrical shank of the bit. As shown the shank 1 is externally threaded for detachable connection to the usual tubular bit

stem through which water under pressure is supplied, and by which the bit is rotated. The lower end of the shank 1 is flattened to form a pair of wings 2, which terminate in cutting edges 3. To facilitate the sharpening of these cutting edges 3, the above referred to flattened end of the shank is provided on its opposite sides with centrally arranged longitudinally extending grooves 2'.

The upper end of the shank 1 is provided with a pair of diametrically opposite longitudinally extending bores 3', the plane passing through the axes of which is disposed at right angles to the wings 2, while the lower end of the shank is provided with pairs of diagonal intersecting bores 4, the upper intersecting ends of which communicate with the longitudinally extending bores 3'. These diagonal bores 4 are bent into parallel relation with respect to the longitudinally extending bores 3' as shown, and have their free ends disposed above the cutting edges of the wings 2 and on opposite sides of the same. The bores 4 are preferably of rectangular configuration in cross section as shown clearly by Fig. 4 of the drawings, whereby a substantially flat stream of water is fed to the opposite sides of the wings 2 thereby reaching all points of the bit.

From the foregoing it may be seen that when the water under pressure is supplied to the bit it will effectively prevent gumbo or other earthy material from sticking upon the same and thus the object of the invention has been effectively carried out.

As various minor changes in form, proportion, and in the minor details of construction may be resorted to without departing from the spirit of this invention, I do not wish to be limited to the construction herein shown and described other than that set forth in the appended claim.

Claim:

A drill bit of the class described comprising a shank provided with a pair of diametrically opposite longitudinally extending bores and having one of its ends flattened to form a pair of wings, the latter being disposed at right angles to the plane passing through the axes of said bores and terminating in cutting edges, said shank being further provided with pairs of diagonal intersecting bores having one of their ends communicating with said longitudi-

nally extending bores, said diagonal bores being bent into parallel relation with respect to said longitudinally extending bores and having their other ends located on the opposite sides of said wings and above the cutting edges thereof.

In testimony whereof I have hereunto set

my hand in the presence of two subscribing witnesses.

ROBERT DRURY MARTIN.
